(57) **CLAIM**

The ornamental design for a gun brush, as shown and described.

DESCRIPTION

FIG. 1 is a front, right, top perspective view of the first embodiment of a gun brush, showing my new design; FIG. 2 is a rear, left, bottom perspective view thereof; FIG. 3 is a front elevational view of the reduced scale thereof;

FIG. 4 is a rear elevational view of the reduced scale thereof; FIG. 5 is a left side view of the reduced scale thereof; FIG. 6 is a right side view of the reduced scale thereof; FIG. 7 is a top plan view of the enlarged scale thereof; FIG. 8 is a bottom plan view of the enlarged scale thereof; FIG. 9 is an enlarged view of detail 9 in FIG. 1; FIG. 10 is an enlarged view of detail 10 in FIG. 2; FIG. 11 is an enlarged view of detail 11 in FIG. 3; FIG. 12 is an enlarged view of detail 12 in FIG. 7; FIG. 13 is a front, right, top perspective view of the second embodiment of a gun brush, showing my new design; FIG. 14 is a rear, left, bottom perspective view thereof; FIG. 15 is a front elevational view of the reduced scale thereof;

FIG. 16 is a rear elevational view of the reduced scale thereof; FIG. 17 is a left side view of the reduced scale thereof; FIG. 18 is a right side view of the reduced scale thereof;

FIG. 19 is a top plan view thereof; FIG. 20 is a bottom plan view thereof; FIG. 21 is an enlarged view of detail 21 in FIG. 13; FIG. 22 is an enlarged view of detail 22 in FIG. 14; and, FIG. 23 is an enlarged view of detail 23 in FIG. 15.

The dashed broken lines in the figures are for the purposes of illustrating portions of the gun brush and form no part of the claimed design.

The dash-dot-dash broken lines are for notating enlarged views and form no part of the claimed design.

1 Claim, 23 Drawing Sheets
